UNITED STATES PATENT OFFICE.

HENRY COATES, OF WATFORD, ENGLAND.

ELECTRIC-ARC FURNACE.

1,308,624.

Specification of Letters Patent.

Patented July 1, 1919.

Application filed November 27, 1918. Serial No. 264,392.

To all whom it may concern:

Be it known that I, HENRY COATES, a subject of the King of England, residing in Watford, Hertfordshire, England, have invented certain new and useful Improvements in Electric-Arc Furnaces, of which the following is a specification.

This invention relates to electric arc furnaces and the means whereby they are regulated. It is customary at the present time to provide such furnaces both with hand-operated means for raising and lowering the electrodes and with automatic means for adjusting them. The hand-operated means are commonly employed when the furnace is started and when approximately stable conditions have been reached the duty of adjusting the electrodes is transferred to the automatic gear. Such automatic gear or automatic "regulators" are both well-known, and are of more than one kind. The type of such regulator to which the present invention in part relates, is that which has its action determined by the strength of the current flowing through the arc, and it is hereinafter referred to as "an automatic regulator controlled by the current-strength of the arc."

Automatic regulators of the kind defined, controlled by the current-strength of the arc, are sometimes arranged to move the electrode or electrodes in the direction determined by the automatic control, not with a continuous movement, but by a succession of short movements separated from one another by short periods of rest; the object of this arrangement is to prevent hunting and a regulator arranged in this manner is hereinafter described as "a step-by-step regulator".

All automatic regulators of the step-by-step type controlled entirely by the current-strength of the arc are open to the objection that on certain classes of work, such for example as the melting of turnings and borings, they do not respond at all times in such a way as to prevent tripping the circuit-breaker for the furnace. Each time a circuit-breaker is tripped, and the furnace has to be re-started, a loss of time occurs which, in the case of a reasonably large plant, may be so long as a quarter of an hour, and this loss of time is very objectionable. The present invention has for its prime object the obviating of risk of tripping the circuit-breaker in the said manner

but has other objects which will hereinafter appear.

According to the present invention there is combined with an arc-furnace an automatic regulator controlled by the current-strength of the arc, a voltage-controlled automatic switch having two or more positions controlled by the voltage at the arc, and means so connecting the switch with the said regulator that in one position the switch permits the said automatic regulator to operate in its normal manner but in the other position co-operates with other parts of the apparatus so that the arc is lengthened at a more rapid rate than by the normal operation of the said regulator.

Preferably the voltage-sensitive portion of the said switch is constructed to move a live contactor between two yieldingly supported contact pieces whereof one affords an idle circuit and the other forms part of the operating circuit for the switch and the parts are so constructed that the contactor does not, when moving in either direction, break circuit with one said contact piece until after it has made circuit with the other. By this means the voltage-sensitive device does not have to break a single circuit at any time but only one of two circuits connected in parallel; this tends to durability of the contacts and other advantages.

The present invention further provides that the said switch controls a second switch closed electro-magnetically on to its contacts in each of its said two positions. Other features of novelty will hereinafter appear and are pointed out in the claims.

The accompanying drawings illustrate one embodiment of this invention intended to be employed as an accessory to an automatic step-by-step regulator.

Figure 1 being a front view of the automatic switch portion, and

Fig. 2 a similar view of the voltage-sensitive device controlling the switch of Fig. 1.

The parts are shown in such positions that the switch of Fig. 1 is at the commencement of the movement called for by the position of the parts of Fig. 2. The switch of Fig. 1 is operated by a solenoid A whose plunger A¹ carries a yoke A² each end of which is linked by a link A³ to one of two pivoted switch arms B pivoted at B¹. Each switch arm B co-operates with two contacts C and D, and the arm carries a tail piece B² on

which is mounted a roller B^3 to coöperate with a cam-track E^1 carried by an arm E pivoted at E^2 . Beneath each arm E , which constitutes a switch arm, is a yieldingly mounted carbon block F ; suitable stops and return springs are provided for the arms E .

Below the yoke A^2 the plunger carries an armature G^1 for an electro-magnet G mounted on the panel below the switch. The yoke A^2 and the armature G^1 are resiliently connected in any convenient manner to the plunger, as for example through the medium of the coiled spring A^4 .

To the right-hand side of the panel is a voltage-sensitive device comprising a coil H mounted on the center limb of a block of U-shaped stampings H^1 between whose polar embrace is a pivoted armature H^2 of stampings carrying short-circuited coils H^3 . Fast upon the spindle of the armature H^2 is a tongue J constituting a contactor, to play between two carbon contact pieces J^1 slidably and resiliently mounted in boxes in such a way that as the contactor moves away from one in the direction of the other, the former follows it until the other has been reached, but so that continued movement of the contactor causes it ultimately to leave the first said block and break circuit therewith. Suitable controls are provided for the armature H^2 and some such are indicated by the dashpot K and counterweight K^1 . The coil H is connected by the wires h across the arc which it is desired to control by the means illustrated.

Above the voltage-sensitive device H H^2 is a small electrically operated switch comprising a magnet L , its pivoted armature L^1 , and a pivoted switch arm L^2 weighted or spring controlled to tend constantly to assume the position in which it is shown in the drawing. The free end of the arm L^2 plays between two contacts L^3 L^4 whereof L^4 is a dummy.

The electrical circuits of the apparatus are indicated in full lines, chain lines, and dotted lines, indicating respectively, a heavy current supply of direct current, a light current control circuit fed with direct current and a light control circuit fed with alternating current.

The contacts C are connected by wires c to the Thury regulator or hand control feed supply and serve to bring supply current controlled by it through the switch arms B and the wires b to the armature of the electrode-operating motor. The wires b are also tapped into connection with the arms E , and the carbon blocks F are connected through their housings to the two ends of a braking resistance f . The motor has its shunt field constantly excited independently of the circuits indicated in the drawing.

A supply of direct current power at the full voltage at which the electrode motor

may be operated, is brought by the wires d to the contacts D .

From the right-hand contact D two control circuits are taken, the upper one by the wire l through the contact L^3 and the wire a 70 to the solenoid A , from which a wire a^1 continues the circuit to the left-hand contact D .

The other control circuit passes by way of a limiting resistance R to the contactor J 75 which is thus always alive, and thence by way either of the upper or of the lower carbon J^1 . In the drawing the path is by way of the lower contact and the wire j direct to the left-hand main at D . A tapping is taken from the wire j to the coil of the magnet G this circuit being completed by way of the wire g , and the winding of the magnet L to the upper carbon J^1 .

When the parts are in the position shown 85 in the drawing the voltage across the arc has fallen to a value below that which it is desired to maintain and the contactor J has therefore fallen on to the lower carbon block. In this position there is no circuit 90 through the magnets L and G , and the armature of the former therefore drops and its switch arm L^2 closes upon the contact L^3 ; moreover the magnet G being now unexcited its armature G^1 is free. The plunger A^1 is 95 thereupon pulled upward and the circuit at the contacts C interrupted thereby disconnecting the motor from the ordinary automatic control. As the plunger moves upward the rollers B^3 press the arms E on 100 to the contacts F thus momentarily connecting the motor armature to the braking resistance f and finally the circuit to the motor armature is established from the contacts D through the arms B , the brake resistance being in this position disconnected. The motor armature is now supplied with an uninterrupted supply at full voltage from the contacts D through the arms B and wires b .

It therefore revolves in the direction to raise 110 the electrode and does so at the maximum speed obtainable. Meanwhile the current is flowing idly from the right-hand contact D through the resistance R and the contactor J to the left-hand block D . As the electrode rises and the voltage across the arc increases the contactor J slowly rises until it meets the upper block J^1 which causes the circuit composed of the magnets L and G in series with one another to be put in parallel with the wire j . They are thus, if energized at all, energized too feebly to effect any movement of their armatures. Further rise in the voltage at the arc causes the contactor to rise still further until eventually 115 it breaks circuit with the lower block J^1 . This causes the magnets L and G to be fully energized, and the former throws the switch arm L^2 so interrupting the circuit through the solenoid A . The plunger A^1 thereupon 120

125

5 drops, bringing the parts connected with it into the positions shown in the drawing and the armature G^1 completes the movement forcibly and insures sound contact upon the blocks C . As this movement is in progress the braking resistance f is again momentarily applied to the motor armature, thus preventing overrunning.

10 In the normal operation of a 3-phase furnace as heretofore practised, without the aid of this invention, and when employed for the melting down of iron and steel turnings and borings, it is started by throwing the automatic regulator out of operation and 15 by putting manual labor on to each of the three electrodes, switching on the high-tension side of the usual transformer feeding the furnace, and carefully and gradually lowering each electrode by the said manual 20 labor. In result the charge on the hearth becomes gradually heated and when this has proceeded sufficiently far for the production of a substratum of liquid metal, the duty of controlling the electrodes is transferred from 25 the operatives to the automatic regulator. It, however, frequently happens that, a cavity having been formed in the mass of the charge, the material forming the side of such cavity suddenly falls in, short-circuiting 30 the arc in the cavity and eventually tripping the circuit-breaker. At such times the tripping of the breaker may be avoided if the electrode can be raised with sufficient rapidity.

35 It will be observed that the apparatus provided by this invention may form a simple addition to existing plant. Should the switch on the regulator for raising the electrode be an electro-magnetically operated 40 switch, then the particular construction of parts shown in Fig. 1 may be dispensed with if desired, and the parts of Fig. 2 be so connected to the said switch as to operate it in the manner provided by this invention. 45 This invention enables manual control of the electrodes to be dispensed with. The furnace may thus be started up cold and switched in and out and otherwise handled in the ordinary way but without the need 50 for manual adjustment of the electrodes at starting, nor subsequently.

If for any reason the supply of power to the transformer or transformers supplying the furnace is cut off, the furnace electrodes 55 will not, with the arrangement provided by this invention, remain close to or in contact with the charge nor will they, (as with the ordinary Thury regulator under current-control alone), feed continuously down into the furnace charge until solid opposition is 60 met with, either of which conditions is liable to result in severe short circuits, unless great care is exercised by the semi-skilled operators when reclosing the switch.

65 The present invention meets these condi-

tions by the automatic raising of the electrode quite clear from the charge immediately the voltage is cut off, until, at the upward limit of travel of the electrode, a limit switch (either existing or which could 70 be readily installed) stops this movement automatically; thereafter the main switch can be closed and the electrodes moved down to the charge without danger of serious short circuits.

75 A further advantage results from the fact that the load variation on automatic furnace regulators of the kind in which the control is dependent on the current-strength of the arc, is sometimes obtained by an arrangement in which the combined current in the regulator coil and a load adjusting circuit is kept in a predetermined ratio to the main furnace current.

80 It sometimes occurs in practice that these adjustments having been set for a certain load current in each electrode, conditions of the charge in the furnace afford a contact sufficient for small currents but of insufficient area for the large current for which 85 the regulator has been set. The regulator then supplies energy to the electrode motor to drive the electrode downward to obtain an increase of current up to the predetermined value, and this frequently results in 90 broken electrodes. With the attachment provided by this invention, a contact of this nature would result in the electrode being first raised and then lowered until the area of contact had been improved by the normal 95 smelting effect of the current, and the usefulness of the regulation given by such current-strength regulators is thus enhanced.

100 What I claim as my invention and desire to secure by Letters Patent is:—

1. The combination with an arc-furnace automatic regulator controlled by the current-strength of the arc, of a voltage-controlled automatic switch having two or more positions controlled by the voltage at the 110 arc and means so connecting the switch with the said regulator that in one position the switch permits the said automatic regulator to operate in its normal manner but in the other position co-operates with other parts 115 of the apparatus so that the arc is lengthened at a more rapid rate than by the normal operation of the said regulator.

2. Apparatus according to claiming-clause No. 1 wherein the voltage-sensitive portion 120 of the said switch is constructed to move a live contactor between two yieldingly supported contact pieces whereof one affords an idle circuit and the other forms part of the operating circuit for the switch and the 125 parts are so constructed that the contactor does not, when moving in either direction, break circuit with one said contact piece until after it has made circuit with the other, for the purpose described.

3. Apparatus according to claiming-clause No. 1 wherein the said switch controls a second switch closed electro-magnetically in each of its said two positions for the purpose 5 described.

4. The combination with the switch of claiming-clauses No. 1 and No. 3 of means

operated by the switch to put a brake for the arc-adjusting motor on and off automatically as the switch passes from one position to the other. 10

In testimony whereof I affix my signature.

HENRY COATES.
